UNITED STATES PATENT OFFICE.

FRANCIS M. ROUSH, OF MIDDLEBURY, INDIANA.

GRAIN-TALLY.

SPECIFICATION forming part of Letters Patent No. 413,835, dated October 29, 1889.

Application filed March 23, 1889. Serial No. 304,420. (No model.)

To all whom it may concern:

Be it known that I, FRANCIS M. ROUSH, a citizen of the United States of America, residing at Middlebury, in the county of Elkhart and State of Indiana, have invented certain new and useful Improvements in Grain-Registers, of which the following is a specification, reference being had therein to the accompanying drawings.

My invention relates to improvements in grain-registering machines in which a rotary measure-carrier operates in conjunction with registering mechanism to keep tally of the number of measures passed through the machine; and the objects of my improvement are to produce a machine of this class of compact and simple construction, in which the rotary measure-carrier is provided with open sides to facilitate the introduction and removal of the measures and adjustable means to level the top of the grain therein. I attain these objects by the construction illustrated in the accompanying drawings, in which—

Figure 1 is a perspective view of a grain-registering machine constructed in accordance with my invention. Fig. 2 is a longitudinal vertical section of the same. Fig. 3 is a top view of the registering mechanism.

In said drawings, A represents a frame, that may be supported upon trestles A² or upon legs. Said frame has three sides A³, that may be closed or provided with openings a, for the escape of grain overflowing from the measures; but one of the sides is entirely open to facilitate the admission and removal of the measures. The bottom A⁴ has also openings a² for the escape of overflowing grain. The top A⁵ carries the hopper a³, through which grain is poured into the measures. Within the frame A is placed the skeleton or open-side measure-carrier, consisting of a disk B, upon which the measures C are placed. In the present instance three measures are used, and on a level with the top of said measures the measure-carrier has three segmental arms B², to facilitate the removal and transfer of the grain, overtaking one measure into the succeeding one. The arms B² are united to the bottom

disk B by means of three standards B³; but between said arms and standards there are openings to permit the measures to be slid out of the rotating carrier without requiring them to be lifted above the surface of the bottom disk. To facilitate the rotation of the carrier, the under side of the disk B is provided with a hub b, and through said hub and the disk, and also through the arms B², passes a long bolt or shaft D, that also unites the top and bottom of the frame A together. The disk B has also a series of large perforations b², to permit the grain spilled from the measures while leveling them to escape from the machine.

To scrape off the surplus grain in the filled measures, a scraper E is adjustably secured to one edge of the top A⁵ by means of two screws e, passing through vertical slots e² in said scraper.

To keep tally of the number of measures passed through the machine, each standard B³ between said measure is provided with an inclined or beveled projection b³, to come in contact or in gear with one of the pins f, projecting horizontally from the face of the wheel F, that is pivoted at f² to the side of the machine, with its upper edge extending through the top thereof. Within a casing G, hinged to said top at g, are located two multiplying gear-wheels H and J. The wheel F has besides the ten pins f, projecting from its face, a pin f³, projecting from its periphery, and said pin f³ is adapted to engage at each revolution with one of the ten pins h, projecting horizontally from the wheel H, and said wheel carries, also, a vertical pin h², which is adapted to engage at each revolution with one of the ten teeth of the wheel J. The three wheels F H J carry, also, numbers from 0 to 9, so that the number of measures passed can be read through the glass g² in the top of the casing G. The periphery of the wheel F is also provided with ten ratchet-notches, within which one end of the pawl f⁴ enters to prevent its retrograde movement.

Having now fully described my invention, I claim—

A grain-register consisting of a frame hav-

ing a hopper in the top and perforations in the bottom and side thereof, a revolving measure-carrier having open sides, a perforated bottom disk, removable measures therein, 5 and segmental arms level with the top of said measure, standards uniting said disk and arms, laterally-extended beveled projections upon said standard, and registering gearing

operated by said projections, substantially as described.

In testimony whereof I affix my signature in presence of two witnesses.

FRANCIS M. ROUSH.

Witnesses:

JACOB P. MILLER,

ISAAC J. BOUTRAGER.
